CLAIM

The ornamental design for a plant bender, as shown and described.

DESCRIPTION

FIG. 1 is a top, front and right side perspective view of a plant bender embodying my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines depict portions of the plant bender that form no part of the claimed design.

1 Claim, 4 Drawing Sheets
